UNITED STATES PATENT OFFICE

WILLIAM A. READY, OF BROOKLINE, MASSACHUSETTS

D-HANDLE

Application filed September 4, 1930. Serial No. 479,665.

My invention aims to provide improvements in D-handles for shovels and the like, and the method of assembling the casing.

Reference is hereby made to my divisional application Serial No. 521,180, filed March 9, 1931.

In the drawing, which illustrates a preferred embodiment of my invention:

Figure 1 is an elevation view of my invention showing the upper end of a split stale incased in a sheet metal casing;

Fig. 2 is a view of the sheet metal casing before attachment to a stale, the lower portion being in cross-section to show the means which holds the parts of the casing in assembled relation;

Fig. 3 is a part section and part elevation of a portion of the casing showing the method of assembly of the two parts;

Fig. 4 is a view of the parts shown in Fig. 3 after they have been completely assembled; and

Fig. 5 is a section taken on the line 5—5 of Fig. 4.

With reference to the drawing, I have shown a D-handle which includes a casing 1 preferably formed from sheet metal and combined with the split end of a stale 2 and a grip piece 3, as shown in Fig. 1. The general construction of the handle, except for the means by which the casing parts are secured together, and the method of assembly of the three parts of the handle is substantially the same as shown and more fully described in my co-pending application Serial No. 341,131, filed February 19, 1929. Since my present invention relates to improvements in the casing and the method of assembling the parts thereof, it will not be necessary to describe in detail the general construction of the handle and the method of assembly.

My improved casing 1 is formed from two identical hollow sheet metal parts, each of which is semi-cylindrical in cross-section and has a flat face provided by inwardly bent flanges 4, 4 as shown in Figs. 4 and 5. Each part also has a vertical flange 5 adjacent to the stale-receiving end and a hook shaped

portion 6 extending from one end of a flange 4, as best shown in Fig. 2.

When the parts of the casing 1 are secured together, as shown in Fig. 2, the flange 5 of one part underlies a portion of another part (Fig. 5) and is welded thereto to secure the parts together. Also, the hook portions 6 hook under the terminal edges of flange portions 4 (Fig. 2), so that when the side arms of the casing are bent into Y-shaped formation the casing will not spread beyond the hook portions and therefore the stale will not be split.

While the handle construction shown and described in my co-pending application referred to above is satisfactory for general purposes, it has been found that the casing parts will pull apart where they are joined together when placed under heavy strain such as when the handle is used for a "pry". Therefore I have overcome this objection by the construction used in my present form of device because, when the wooden arms of the stale are forced into the hollow arms of the casing 1, the hook portions are held tightly against the flanges 4 and provide, with the welded portions, a strong durable connection to prevent separation of the casing and splitting of the stale beyond that point.

The method of assembling the parts of the casing is, I believe, unique because the construction is such that the parts can be assembled only by placing them together with their flat faces in engagement and with the longitudinal axis of one part angled relative to the longitudinal axis of the other, as shown in Figure 3. This is necessary because of the opposed hooks which can be engaged beneath the flanges 4 only in this manner and thereafter rotating one part relative to the other to bring them into the positions shown in Figs. 2 and 4. By this method of assembly, all of the elements may be preformed and then the casing may be welded along the lines of the underlying flanges 5 (Fig. 5) to secure the parts together and thus form a strong durable casing, as shown in Fig. 2. The hook portions are offset from the center (5) of each

casing part so as not to interfere with each other and to facilitate assembly as well as to provide a strong assembly across the entire width of the casing.

5. When the parts are assembled by the method just described they are securely fixed together at one end and the outer surface is smooth and presents a neat appearance.

While I have illustrated and described a 10 preferred embodiment of my invention, I do not wish to be limited thereto because the scope of my invention is best defined by the following claims, some of which are intended to be of such scope as to cover other variations one of which is shown in my co-pending application filed herewith.

Claims.

1. In a D-handle construction for shovels and the like, a sheet metal casing composed of 20 two similar pieces each having a flat inner face facing the flat face of the other and each piece having means adjacent to its flat face interlocked with the other piece to lock the two pieces together.

25. 2. In a D-handle construction for shovels and the like, a sheet metal casing composed of two similar pieces each having a flat inner face facing the flat face of the other and each piece having a hook-like finger extending 30 from the flat face and engaging the material of the flat face of the other piece to lock the two pieces together.

3. In a D-handle construction for shovels and the like, a sheet metal casing composed of 35 two similar pieces each having a flat inner face facing the flat face of the other and each piece having means adjacent to its flat face interlocked with the flat face of the other piece to lock the two pieces together prior to 40 assembly of the casing with a stave, and each of said pieces having a flange overlapping a portion of the other piece and being welded thereto to cooperate with the interlocked means to secure the parts of the casing together.

45. 4. In a D-handle construction for shovels and the like, a sheet metal casing composed of two similar pieces each having a flat inner face facing the flat face of the other and each piece having a hook-like finger extending from one edge of the flat face and being hooked over an edge of the flat face of the other piece thereby to lock said pieces against separation by movement transverse to the axis 50 or parallel with the axis of the casing, said hook-like fingers being engaged over the edges of the flat faces by turning movement with the flat faces in engagement as illustrated and described.

60. 5. In a D-handle construction for shovels and the like, a sheet metal casing composed of two similar pieces each having a flat face facing the flat face of the other and each piece having a hook-like finger extending 65 from one edge of the flat face and being

hooked over an edge of the flat face of the other piece thereby to lock said pieces against separation by movement transverse to the axis or parallel with the axis of the casing, said hook-like fingers being engaged over 70 the edges of the flat faces by turning movement with the flat faces in engagement as illustrated and described, and each of said pieces having a flange overlapping the other piece and welded thereto to cooperate with the said hook-like fingers to secure positive assembly of the pieces at one end of the casing.

6. In a D-handle construction for shovels and the like, a sheet metal part composed of 80 two similar pieces each having a flat face facing the flat face of the other and each piece having a vertical flange adjacent to one end and overlapping the other piece and welded thereto thereby to secure said two 85 pieces rigidly together.

7. In a D-handle construction for shovels and the like, a sheet metal casing composed of two similar pieces each having a flat face facing the flat face of the other and each piece having a vertical flange adjacent to one end and overlapping the other piece and welded thereto thereby to secure said two pieces rigidly together, said flat faces terminating adjacent to the upper ends of said 95 flanges and each having a portion hooked under the edge of the other flat face to strengthen the said casing against being pulled apart adjacent to the welded flanges.

8. A casing for a D-handle comprising two 100 sheet metal parts each having flanges 4, 4 providing a flat inner face, and a hook-like portion 6, extending from the lower edge of a flange 4 to engage beneath the lower free edge of a flange 4 on the other part, 105 thereby to secure the said parts in interlocked relation adjacent to one end.

9. A casing for a D-handle comprising two 110 sheet metal parts each having flanges 4, 4 providing a flat inner face, and a hook-like portion 6 extending from the lower edge of a flange 4 to engage beneath the lower free edge of a flange 4 on the other part, thereby 115 to secure the said parts in interlocked relation adjacent to one end, and each part having a vertical flange 5 overlapping the edge of the other part and being welded thereto rigidly to secure the parts together at the end adjacent the hook portions 6, 6.

10. In a D-handle construction for shovels and the like, a sheet metal part composed of two similar pieces bent into a Y-shaped formation and each piece having integral interlocking means engaged with the other 125 prior to securing the two pieces together adjacent to one end of the sheet metal part.

11. In a D-handle construction for shovels and the like, a sheet metal part composed of two similar pieces bent into a Y-shaped for- 130

mation and each piece having portions overlapping the other piece and secured thereto thereby to secure the two pieces together adjacent to one end of the sheet metal part.

5 In testimony whereof, I have signed my name to this specification.
